UNITED STATES PATENT OFFICE.

SHERMAN H. PAXTON, OF MINNEAPOLIS, MINNESOTA.

DISPENSING AND PRINTING DEVICE FOR PAPER TAPE.

1,263,597.

Specification of Letters Patent. Patented Apr. 23, 1918.

Application filed October 22, 1917. Serial No. 197,846.

To all whom it may concern:

Be it known that I, SHERMAN H. PAXTON, a citizen of the United States, residing at Minneapolis, in the county of Hennepin and 5 State of Minnesota, have invented certain new and useful Improvements in Dispensing and Printing Devices for Paper Tape, of which the following is a specification.

My invention relates to dispensing and 10 printing devices for paper tape, and has for its object to provide convenient means for holding rolls of paper strip in position to be easily drawn out for use in lieu of twine or tape for securing bundles. The holding 15 mechanism is combined with devices for printing any desired legend, as the name of a dealer, the trademark of special goods, in conjunction with the dealer's name, as may be desired, upon the tape as it is drawn out, 20 and also for applying to the tape or strip mucilage or other gumming material by which the same is secured upon a bundle to hold it closed.

The means for effecting the above indicated 25 results are economically and efficiently disposed and coöperate with the utmost accuracy in producing the desired results.

The full objects and advantages of my invention will appear more fully in connection 30 with the detailed description thereof and are particularly pointed out in the claims.

In the drawings, illustrating the application 35 of my invention in one form,—

Figure 1 is a side elevation in part fragmentary, of an embodiment of my invention. Fig. 2 is a sectional elevation of part of the mechanism shown in Fig. 1. Fig. 3 is a side elevation of the device viewed from the opposite side from Fig. 1. Fig. 4 is a sectional fragmentary view showing the manner of mounting the reel. Fig. 5 is a detail of the securing means. Fig. 6 is a detail showing the manner of holding the mucilage applying roller in position. Fig. 7 is a sectional detail showing the manner of supporting the guide rollers.

As illustrated, the paper tape or strip 10 is wound in a roll 11 upon a central reel 12, 50 having side walls 13. A base frame member 14 has a standard 15 which carries a spindle 16 upon which reel 12 is journaled.

The spindle 16 is threaded at the outer end 17, the threaded portion being cleft, as indicated at 18. Within the cleft 18 is the central portion 19 of a figure 8 washer 20, illustrated in detail in Fig. 5. Threaded upon the portion 17 is a nut 21 which engages the washer 20 and through engagement thereof with one wall 13 of the reel 12 forces the other wall against tensioning springs 22. By screwing down a greater or less extent on the hand nut 21 the proper tension at which to feed the paper tape 10 is secured. The strip of tape 10 passes from the roll 11 65 beneath a guide roller 23 journaled upon a screw pin 24 threaded into a boss 25 on a standard 26 formed in conjunction with base member 14. From beneath roller 23, the tape 10 passes over a platen roller 27 journaled upon a screw pin 28 carried in standard 26 and from which the tape passes backward beneath a guide roller 29 journaled upon screw pin 30 supported in a boss 31 on standard 26. From beneath roller 29, the 70 tape passes over the gumming roller 32 which has trunnion extensions of its shaft 33 extended into slots 34 and 35 in the side walls 36 and 37 of base member 14, said trunnion extensions also passing into notched 75 slots or open ended slots 38 and 39 of the receptacle 40 which contains the gumming fluid or the water. This receptacle is thus locked into position by the trunnion extensions of shaft 33 but is readily withdrawn 80 through the open end of the base member box 41 by simply lifting out gumming roller 32.

It is obvious that the receptacle 40 may contain mucilage which is directly applied 90 to the strip of tape 10 by the roller 32, or, as is more commonly the practice, the tape 10 may itself have been previously gummed and the receptacle 40 contain water for moistening the gummed surface. In either 95 event, the material within the receptacle 40 is in the first instance or soon becomes impregnated with organic matter which undergoes decomposition, and in time becomes very foul unless the same is frequently 100 changed and the receptacle 40 properly cleansed. It is, therefore, essential that the water receptacle or receptacle for the mucilage should be readily removable, and the

arrangement herein described is very simple and efficient for that purpose. The tape 10 finally passes over a serrated cutting knife 44 mounted upon a cross rail 45 at the end 5 of box member 41, by which the tape may be conveniently cut into such lengths as are desirable.

The several rollers 23, 27, and 29, heretofore described as well as printing and inking rollers hereafter described, are each 10 preferably journaled, as shown in Fig. 7 wherein the screw pin 30 is shown threaded into boss 31 of standard 26, and this screw pin is surrounded by a sleeve 46 but extends 15 inside of bushings 47 and 48 fast on the roller 29.

Mounted for oscillation upon the screw pin 24 is a carrier 49 having side walls 50, 51 which form the journal supports of said 20 carrier and which are connected by top piece 52, as clearly shown in Fig. 2. Journaled upon a fixed shaft 53 extending between the walls of carrier 49 is an inking roller 54. A printing roller 55, having its 25 trunnions 56 extending into slots 57 at the front side of carrier member 49 is normally held in contact with platen roller 27 or with the tape 10 where the same passes over the platen roller 27 by the weight of the carrier member 49, which, as shown, is pivoted to pin 28 so as to tend to fall forward and bring the printing roller 55 into contact with platen roller 27. An ink applying roller 58 has a bearing in blocks 59 extending through apertures 60 in the sides 50 and 51 of carrier member 49. The blocks 59 have connected thereto springs 62 which are also connected with the side members 50 and 51 and which operate to hold the ink 35 applying roller at all times in contact with both the inking roller 54 and the printing roller 55.

The operation of my invention has been given with considerable fullness in connection 45 with the description of the several parts. It is apparent that the printing roller 55 may readily be removed and changed, merely by swinging backward the carrier 49; and whenever replaced is immediately 50 and automatically brought into proper contact with the plate over platen roller 57 and the inking roller 58. The entire operation of printing and moistening the strips of tape as well as tearing them into the proper 55 lengths is affected by merely drawing the strip outward either in engagement with moistener roller 32, or out of engagement therewith as may be desired. A spring tension device 64 is secured to box member 41 60 operating to take up slack in the strip and hold the same properly tensioned as it is drawn out. Although the weight of carrier member 49 is usually all that is necessary to impress the printing roller 55 with sufficient force upon the take 10 as it passes

over platen roller 27, I provide also a spring 65 for aiding gravity in effecting this operation.

It will thus be seen that I have provided a simple and effective construction for dispensing paper tape and printing and gumming or moistening the same as it is drawn from the reel in which all of the parts are readily removable for examination, replenishment, cleansing or repair. 75

I claim:

1. A dispensing device for paper fastening-tape comprising means for holding a roll of said tape, guide rollers under and over which said tape passes from the roll to bring a loop thereof in an elevated exposed position, a pivoted carrier having a front wall normally overhanging said exposed loop and being provided with open ended slots, and a printing roller removably positioned in said slots and held by the carrier in contact with the exposed loop of tape. 80

2. In a dispensing device for paper fastening tape, means for guiding the tape to bring it into exposed position, a pivoted carrier normally overhanging the tape at such exposed position, and a printing roller having its trunnions positioned in open-ended slots in said carrier whereby said roller is removably held by the carrier in contact 95 with the exposed portion of the tape.

3. In a dispensing device for paper-fas-tening tape, a platen for guiding and sup-100 porting the tape, a pivoted carrier normally overhanging the tape as it passes over said platen, a printing roller, having its trun-nions positioned in open-ended slots in said carrier whereby said roller is removably held by the carrier in contact with the tape on said platen, and means for moistening 105 the tape as the same passes from the print-ing roller.

4. In a dispensing device for paper-fas-tening tape, means for holding a roll of such tape, a support, printing mechanism 110 mounted on said support, a box-like mem-ber on the lower portion of said support having slots in its side walls, a liquid con-tainer capable of being slid into said box like member and having slots adapted to 115 register with the slots in the side walls, and a liquid applying roller having its trunnions normally lying in both of the aforesaid sets of slots whereby said container is locked in position. 120

5. A dispensing device for paper fastening-tape comprising means for holding a roll of said tape, guide rollers under and over which said tape passes from the roll to bring a loop thereof in an elevated ex-125 posed position, a pivoted carrier having a front wall normally overhanging said exposed loop and being provided with open-ended slots, a printing roller removably po-sitioned in said slots and held by the car-130

rier in contact with the exposed loop of tape, and ink applying means on the carrier which contact with the printing roller when the same is held positioned by the carrier against the exposed loop of tape.

6. A dispensing device for paper fastening-tape comprising a base member having a box formed in a portion thereof, means for holding a roll of said tape; means for

guiding the tape from said roll, a receptacle removably positioned in the base box, and a moisture applying roller in the path of movement of the tape journaled in the base box so as to hold the receptacle positioned therein.
